UNITED STATES PATENT OFFICE.

JOHN GREEN, OF ST. LOUIS, MISSOURI, ASSIGNOR OF ONE-HALF TO F. C. MOOK, OF SAME PLACE.

DESIGN FOR A TONGUE FOR MORTAR-HODS.

SPECIFICATION forming part of Design No. 25,277, dated March 24, 1896.

Application filed February 11, 1896. Serial No. 578,957. Term of patent 14 years.

To all whom it may concern:

Be it known that I, JOHN GREEN, of the city of St. Louis, State of Missouri, have invented a new and original Design for a Tongue for Mortar-Hods, of which the following is a full, clear, and exact description, reference being had to the accompanying drawings, forming a part hereof.

In the drawings, Figure 1 is a perspective view of a mortar-hod tongue, the same embodying my design. Fig. 2 is a side elevation of the tongue.

The leading feature of my design consists in an elongated body triangular in cross-section, from two of the sides of which body project longitudinally-extending rectangular ribs, and from one end of this triangular body projects a slight lug or lip.

1 indicates the elongated body triangular in cross-section, from one end of which projects a lug or lip 2.

3 3 indicate the lips or projections that extend longitudinally along two sides of the body 1, said lips 3 projecting approximately at right angles to the faces of the triangular body 1.

I claim—

The design for a tongue for mortar-hods, substantially as herein shown and described.

In testimony whereof I affix my signature in presence of two witnesses.

JOHN GREEN.

Witnesses:

EDWARD E. LONGAN,
M. P. SMITH.
